(57) **CLAIM**

The ornamental design for a disposable cystoscope, as shown and described.

DESCRIPTION

FIG. 1 is a top perspective view of the disposable cystoscope, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is an enlarged top plan view thereof;

FIG. 7 is an enlarged bottom plan view thereof; and,

FIG. 8 is another perspective view thereof showing the disposable cystoscope in use.

The dash-dash broken lines in the drawings are for the purpose of illustrating portions of the disposable cystoscope that form no part of the claimed design. The dot-dash broken lines in FIG. 8 depict environmental structures and forms no part of the claimed design. The disposable cystoscope is shown with symbolic breaks in its length. Any portions not shown between the break lines form no part of the claimed design.
